UNITED STATES PATENT OFFICE.

CHARLES A. GRAS, OF NEW YORK, N. Y., ASSIGNOR TO FRANCIS DEIMEL,
OF SAME PLACE.

FURNACE APPARATUS.

SPECIFICATION forming part of Letters Patent No. 568,899, dated October 6, 1896.

Application filed February 24, 1896. Serial No. 580,410. (No model.)

To all whom it may concern:

Be it known that I, CHARLES A. GRAS, a resident of the city, county, and State of New York, have invented certain new and useful Improvements in Furnace Apparatus, of which the following is a full, clear, and exact description.

My invention relates to furnace apparatus, and has for its object to produce an apparatus for facilitating the quick burning of the fuel, which is specially applicable to a furnace forming the subject-matter of a companion application filed by me on the 24th day of February, 1896, Serial No. 580,411.

15 To this end my invention consists in the construction hereinafter set forth and claimed.

My invention will be understood by referring to the accompanying drawings, in which—

20 Figure 1 is a longitudinal section through a furnace forming the subject-matter of a companion application and to which the present invention is especially applicable, the same being introduced to illustrate the construction 25 of the said furnace. Fig. 2 is a front elevation of a furnace apparatus embodying my present invention as well. Fig. 3 is an enlarged detail view of a door of the furnace and its connected apparatus, part of the ap-

30 paratus being in section. Fig. 4 is a section on line 4 4 of Fig. 3. Fig. 5 is a plan view of the parts shown in Fig. 3. Figs. 6 and 7 are side and plan views, respectively, of a part 35 of the apparatus hereinafter referred to; and Figs. 8 and 9 are similar views of another part of the apparatus hereinafter referred to.

Referring particularly to Fig. 1, A is the side wall of the furnace; B, the top wall; C, the front wall, and D the back wall or fire-bridge. E is the boiler, which has a steam-dome F, from which a steam-pipe J leads, which pipe is controlled by a suitable valve K, situated near to the steam-dome and having an operating chain or cord c', (or other 40 suitable operating device,) which extends over a sheave L and down in front of the furnace. This steam-pipe extends into the furnace and is provided with jet-forming means b, which project an end jet or jets b' down- 45 ward, preferably against a step d' of the back wall d, and with jet-forming means b², which project an inclined jet or series of jets b³,

which form a curtain over the grate G, and with jet-forming means b⁵, which project side jets b⁴. By this means the smoke and 55 heavier products of combustion are caused to circulate over the coals and be burned, the lighter products of combustion escaping through the steam-curtain. My improvement upon this structure is mainly directed 60 to devices for facilitating the prompt and efficient combustion of the fuel.

By referring to Fig. 2 it will be noted that the furnace-doors N are composite and each consists of a slotted section N', which is covered by a similarly-slotted section N², which is carried upon pins or balls n, so that when the slots in the sections register with one another air will be admitted to the furnace through the door, and when the solid portions 65 n' of the section N² cover the slots in the section N' air will be prevented from passing to the furnace through the door. It will be obvious that between these extreme positions 70 the amount of air entering through the doors 75 will be proportional to the amount of slot left uncovered, all of which will be readily understood.

Referring now particularly to Fig. 3, wherein the mechanism is shown in enlarged detail, it will be observed that the door N is hung upon a shaft N³, with which it turns, the shaft being provided with a bevel-pinion N⁴, which meshes with another bevel-pinion N⁵, carried upon a shaft N⁶ on the front wall 85 of the furnace. Carried also upon shaft N³ and freely moving thereon are sleeves N⁷ N⁸, from which lugs or ears N⁹ project, which lugs or ears are joined by a rod N¹⁰. The lower ear N⁹ is pivotally connected by a link 90 N¹¹ with the sliding member N² of the furnace-door. Mounted also upon the front wall of the furnace or some other place adjacent to the furnace-door is a slide-moving device O, (shown in the present instance as a cylinder O',) within which a piston O² works, which piston has a rod O³, which carries a rack O⁴. The side of the cylinder is slotted for the passage of the toothed segment O⁵, which meshes with the rack O⁴ and is carried upon the shaft O⁶. An arm O⁷ is likewise provided upon the shaft O⁶ and is connected by a flexible connection O⁸ with one 100 of the lugs N⁹. This lug N⁹ is preferably

the one carried upon the sleeve N^8 , which sleeve has a downwardly-projecting lug N^{12} , (shown clearly in Figs. 3 and 6,) which engages with an upwardly-projecting lug N^8 on a sleeve N^4 , which is rigidly carried upon the shaft N^3 below the sleeve N^8 . The cylinder O' is provided with a relief or escape valve O^9 and a regulable air-inlet valve O^{10} . The shaft N^6 may be provided with an arm N^{15} , which may operate the valve N^{16} in the pipe J to regulate the admission of steam to the furnace. Suitable mechanism may intervene between the arm N^{15} and the valve N^{16} , such, for instance, as the arm N^{17} , which is connected with the arm N^{15} by the link N^{18} . The mechanism which has just been described is duplicated upon the other door of the furnace, the pipe J forking, as shown clearly in Fig. 2, for the purpose of regulating the inlet of steam to the fuel nearest the door operated.

Having described the door mechanism, I will now proceed to define clearly some of its uses, purposes, and its mode of operation.

It has been found essential in furnaces to heighten combustion by giving the air access to the coal immediately after the furnace has received a firing, that is to say, as soon as a few shovels of coal have been thrown on an already-burning fire it has been found advantageous to permit access of the air to the coal to insure its prompt ignition. It has likewise been found that the generality of firemen are unreliable in this respect, so that some mechanical substitute for human fallibility has been found desirable. This I accomplish by my mechanism for opening the fire-door and closing the door and causing or permitting the sections of the fire-door to close together slowly, so that for a few seconds after the fire-door is closed air will still be admitted and will be slowly shut off. To that end the handle N^{20} turns the shaft N^6 , communicating motion through the medium of bevel-gears N^5 N^4 to the shaft N^3 , thereby swinging open the furnace-door, and the lug N^{13} , bearing against the lug N^{12} , will cause the sleeve N^8 and its connected sleeve N^7 to turn therewith. The furnace may now be fed or fired with coal. When now it is desired to close the door, the handle N^{20} is given a motion reverse to its former motion, which will have the effect of closing the door to, but the sleeve N^8 , being freely revoluble on the shaft N^3 , will not follow the motion of the shaft N^3 , because there is considerable room for lost motion between the lugs N^{12} and N^{13} . Operating the lever N^{20} to open the door had also the effect of shutting off the steam from the furnace by operating the valve N^{16} , and the movement of the door likewise effected the raising of the piston O^2 by the chain O^8 and segment O^5 , the air escaping through the relief or escape valve O^9 as the piston rose. The parts in Fig. 3 are shown in the position which they have assumed just as the furnace-door is closed, the slots in the section N^2 of

the furnace-door registering with the slots of the section N' of the furnace-door, so that there is an inrush of air through the grating 70 so far; but at this moment air beginning to enter the cylinder O' through the inlet-valve O^{10} and the piston being supported it will begin to descend slowly, its rate of descent depending upon the adjustment of the adjustable inlet-valve O^{10} , and as the piston descends its swings the segment O^5 and its shaft O^6 , thereby pulling upon the flexible connection O^8 and swinging the sleeves N^9 N^7 to slide the door-section N^2 across the face of 80 the door-section N' , which movement will continue as the piston descends, thereby gradually covering the slots in the section N' , so that air will be gradually shut out of the furnace. 85

It will be obvious that this apparatus is capable of modification without departing from my invention.

What I claim, and desire to secure by Letters Patent, is—

1. In a furnace apparatus, the combination of a slotted furnace-door combined with door-operating means, a slotted slide carried upon the furnace-door, a piston provided with a rack, a pivoted toothed arc coöperating with 95 the rack, and a connection between the arc and the slotted slide.

2. In a furnace apparatus, the combination of a slotted furnace-door combined with door-operating means, a slotted slide carried upon 100 the furnace-door, a piston provided with a rack, a pivoted toothed arc coöperating with the rack, and a flexible connection intervening between the arc and the slotted slide, substantially as described.

3. A swinging slotted furnace-door, a vertical shaft connected thereto, a horizontal shaft geared to the vertical shaft, the said two shafts comprising the furnace-door-opening mechanism, a piston provided with a 110 toothed rack, a pivoted toothed arc meshing with the rack, a slotted slide carried upon the furnace-door, and a connection between the slide and the arc comprising in its structure a lost-motion device such as the sleeves 115 N^8 N^{14} and their lugs, substantially as described.

4. A horizontally-swinging vertically-slotted furnace-door combined with operating mechanism therefor, a steam-supply over the 120 furnace-door having a valve therein, the said valve being rigidly connected to the said furnace-door-operating mechanism, a piston carrying a rack, a toothed arc meshing with the said rack, a slotted slide carried upon the 125 furnace-door, and a connection between the arc and the slide whereby the slotted slide will be slowly moved to close the slots in the furnace-door when the door has been closed.
